US0D1081685S

(12) **United States Design Patent** (10) **Patent No.:** **US D1,081,685 S**
(45) **Date of Patent:** **** Jul. 1, 2025**

(54) **DISPLAY SCREEN OR PORTION THEREOF WITH ICON**

(71) Applicant: **Getac Technology Corporation**, New Taipei (TW)

(72) Inventor: **Shih-Hui Cheng**, Taipei (TW)

(73) Assignee: **Getac Technology Corporation**, New Taipei (TW)

(**) Term: **15 Years**

(21) Appl. No.: **29/879,009**

(22) Filed: **Jun. 30, 2023**

(51) LOC (15) Cl. **14-04**

(52) U.S. Cl.

USPC **D14/489**

(58) **Field of Classification Search**

USPC **D14/485-495**

See application file for complete search history.

(57) **CLAIM**

The ornamental design for a display screen or portion thereof with icon as shown and described.

DESCRIPTION

FIG. 1 is a front view of a display screen or portion thereof with icon showing the claimed design; and,
FIG. 2 is another embodiment thereof.

The outer perimeter illustrated by a dot-dash broken lines in the figures represents a display screen or portion thereof and forms no part of the claimed design. The dashed broken lines in the figures show portions of the icon and form no part of the claimed design.

1 Claim, 2 Drawing Sheets
